UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed February 7, 1923. Serial No. 7,523.

My invention relates particularly to the operating mechanism for an enclosed switch of a quick-break type. The main object is to provide a simple, compact, but effective mechanism for opening and closing the circuit with a snap action. In switches of this character the main switch member usually is oscillated approximately 90°, whereas the spring throwing mechanism requires a movement of approximately 180° in order to be most effective. In accordance with my invention I have provided an operating handle which requires a movement of only approximately 60° from the on to off position, and vice versa.

Fig. 1 is a front view of a switch embodying the improvements of my invention, the cover of the box being shown open and broken away, and the switch being in the off or open circuit position.

Fig. 2 is a side view with the cover closed, the operating handle being shown in full lines in the off or open circuit position, and in dot-and-dash lines in the on or closed circuit position.

Fig. 3 is a transverse sectional view showing the switch in the open circuit position.

Fig. 4 shows a detail side view of the operating handle and gear.

Fig. 5 is a side view of the switch proper shown in an outline of the case, the parts of the switch being in the open circuit position.

Fig. 6 is a side view of the operating mechanism.

Fig. 7 is a composite fragmentary view showing the operating handle throwing mechanism and switch contact in the open circuit position, the remainder of the switch and casing being omitted.

Fig. 8 is a side view similar to Fig. 7 showing an operating handle throwing mechanism and switch member in the closed circuit or on position.

Fig. 9 is a fragmentary sectional view showing the hub of the operating and throwing mechanism.

The box 10 may be of any suitable type provided with any suitable form of cover 11.

The switch proper has an insulating base 12 carrying the stationary switch contacts 13 and 14. The rotary insulating drum or carrier 15 loosely carries the main switch

blades 16 and it is pivoted in the side brackets 17. This carrier has a projecting pin 18 which extends through a slot in one of the side brackets. The operating handle 19 is on the outside of the box and the throwing member 20 is mounted on the inside of the box and adapted to engage the pin 18. The throwing spring 21 is supported on the rod 22 which is guided at one end in the forked bracket 23 and connected at the end 24 to the throwing member 20. This throwing member 20 is supported on a disc 25, the edges of which are held by the rivets 26 which bind together the parts of the hub. The bearing washer 27 is supported in the side walls of the box and flanked by discs 28 and 29, which bear against the outer and inner surfaces of the side of the box. The member 29 constitutes a locking plate which cooperates with the latch 30 to hold the cover closed when the switch is in the on position.

The gear 31, which constitutes a part of the hub, is located between the washers 32 and 28. The handle 19 is pivoted at 33 on the side of the box and provided with a gear segment 34 which meshes with the milled gear 31. The throwing member 20 is provided with slots 35 which permit the throwing member and the rivets 26 of the hub to have relative freedom of action.

One or more washers 36 may be interposed between the locking plate 29 and the throwing member 20 so as to space the throwing member the requisite distance away from the inner wall of the box.

To operate the switch it is simply necessary to swing the handle from the position shown in full lines in Fig. 2 to the position shown in dot-and-dash lines. This short motion can be easily effected either by the hand or fingers, or by means of a cord or hook which may be readily inserted in the opening 37. As the handle is swung upwardly, as viewed in Fig. 2, it rotates the gear 31 and hub clockwise. The operation perhaps will be better understood from Figs. 7 and 8, where the direction of the movement of the handle is from left to right instead of up and down, as shown in Fig. 2.

As the pins or rivets 26 reach the ends of the slots 35 in the throwing member 20, the throwing member is rotated clockwise and compresses the spring 21. As soon as the

connection 24 of the spring with the throwing member 20 passes the center line of the hub, the spring will throw the member 20 and cause one arm to engage the pin 18 and throw the switch member 16 into the position shown in Fig. 8, with a snap action, breaking the circuit quickly so as to avoid arcing.

Of course as soon as the spring 21 starts to expand it is out of the control of the operator, who cannot stop the action of the switch member 16 after it has started to open the circuit.

To close the circuit, the operation is reversed the handle 19 is swung to the left, as in Fig. 8, rotating the gear 31 anti-clockwise and compressing the spring 21 until it passes the center line and suddenly throws the member 20 so as to operate the switch member and open the circuit with a snap action.

The operating handle 19 is preferably provided with curved shoulders 38 at the opposite ends of the arcuate slot 39 which engage the toothless section of the gear 31 in the positions of Figs. 7 and 8 and thus serve as stops to limit the swinging movement of the handle. This positive stop prevents any undue strain being applied to the teeth of the rack 34 and gear 31.

It will thus be seen that although the handle has a very short movement and, therefore, can be readily and quickly operated, the throwing mechanism has a maximum movement for properly affecting the quick break action.

It should also be understood that this method of operation may be applied to ordinary switches without quick-break action.

40 I claim:

1. An enclosed switch comprising an oscillating switch member, a spring operated throwing member having lost motion connection with said switch member, a gear having lost motion connection with said throwing member, and a handle having an open-

ing for said gear with an annular gear segment meshing with said gear.

2. An enclosed switch comprising a box, an oscillating switch member and a spring operated throwing member inside of said box having a lost motion connection with said switch member, a gear outside of said box having a lost motion connection with said throwing member, and a handle having an opening for said gear with an annular gear segment meshing with said gear.

3. An enclosed switch comprising a box, an oscillating switch member and a spring operated throwing member inside of said box oscillable through an angle of approximately 180° and having lost motion connection with said switch member, a gear having lost motion connection with said throwing member, and a handle having a gear segment meshing with said gear and oscillable through an angle of approximately 60° , said gear being located between said gear segment of the pivot of said handle.

4. In an enclosed switch, a box, a movable switch member therein, an external gear rotatably supported in the side of the box and connected to said switch member, a swinging handle hinged to the outside of the box and having a toothed segment meshing with said gear and also having shoulders engaging said gear to limit the throw of the handle without straining said teeth.

5. In an enclosed switch, a box, a switch within the box, a switch operating means, a gear member connected with the switch operating means, and a pivoted external switch handle having a gear rack engagement with said gear member, said gear member being located between said gear rack and the pivot of said handle.

6. In an enclosed switch, a pivoted operating handle having a slot with gear teeth along one edge, and a gear meshing with said teeth and serving as a stop co-acting with the end of said slot.

BENJAMIN E. GETCHELL.
